UNITED STATES PATENT OFFICE

2,231,509

FUSE CONSTRUCTION

William O. Schultz, South Milwaukee, Wis., assignor to Line Material Company, South Milwaukee, Wis., a corporation of Delaware

Application August 26, 1939, Serial No. 292,039

21 Claims. (CL 200—114)

This invention relates to fuse constructions and is particularly directed to a drop-out fuse.

Objects of this invention are to provide a housed type of drop-out fuse in which the fuse slides downwardly after the fuse link has been ruptured and projects from the housing and gives a visual indication that the fuse has blown, and to provide a construction in which a novel form of fuse link extracting means is employed for quickly extracting any remaining portion of the fuse link before the fuse tube has moved away from a stationary contact to thereby prevent pitting of the contacts.

Further objects are to provide a drop-out fuse construction in which a sliding type fuse tube is employed, in which a fuse link extracting member is provided which first extracts any remaining portion of the fuse link and thereafter releases such remaining portion and also detaches itself from a stationary live portion of the apparatus and drops downwardly with the fuse tube itself, such fuse link extracting member being carried by the fuse tube.

This invention, therefore, has for its further object to provide a fuse link extracting means carried by the fuse tube itself so that when the fuse tube slides downwardly after rupture of the fuse link, there are no live projecting parts extending downwardly or outwardly from the housing, but instead in which the fuse link extracting means at the lower portion of the fuse tube is electrically dead, and in which there are no hanging fragments of fuse link.

Further objects are to provide a double lever construction for the fuse link extracting means so that the free end of the lever actively engaging the fuse link executes a motion approximating a straight line downwardly from adjacent the lower portion of the fuse tube, in which such free end of the fuse link extracting means executes a very quick stroke and moves a material distance prior to the release of the fuse link and prior to any motion of the fuse tube, the fuse tube remaining in contact with a stationary contact until after the fuse link extracting means has operated, and thereafter the fuse tube sliding downwardly away from one of the stationary contacts and thus providing an additional point of interruption in the circuit, the first interruption occurring within the fuse tube and being completed prior to the motion of the fuse tube away from the stationary contact.

Further objects are to provide a fuse link extracting means in which the extracting member is protected from the discharging incandescent

gases and initially occupies a position to the side of and protected by the fuse tube itself and thereby not only being guarded against the action of the incandescent gases but also leaving the bore of the fuse tube free and unobstructed. 5

Further objects are to provide a novel form of drop-out fuse in which the fuse link extracting means also automatically holds the fuse link clamped in place without requiring the use of a thumb screw or other member, in which refusing 10 may be accomplished with the utmost ease, and in which the fuse link during refusing may be hooked over the fuse link extracting means and thereafter the fuse link extracting means and the fuse tube may be slightly rotated to move or 15 rock the fuse link extracting means into fuse link clamping position.

Further objects are to provide a novel form of stationary contact including clamping means for the lead-in conductors so that the lead-in conductors may be clamped in a very easy and simple manner.

An embodiment of the invention is shown in the accompanying drawings, in which:

Figure 1 is a vertical sectional view, with parts 25 broken away, showing the parts in their operative positions.

Figure 2 is a fragmentary view of the lower portion of Figure 1, such view being partly in section and partly broken away, showing the final 30 position of the parts after the fuse link has been ruptured.

Figure 3 is a view showing the mounting of the device at an angle instead of vertically as shown in Figures 1 and 2. 35

Figure 4 is a view from the bottom of the device.

Figure 5 is a sectional view on the line 5—5 of Figure 1.

Figure 6 is a view of the fuse tube and door 40 assembly removed from the housing, such view being a bottom view and showing the position of the parts during one stage in refusing.

Referring to the drawings, it will be seen that the device comprises a porcelain or other housing 1 provided with a door 2 of insulating material, such as a phenolic condensation compound. The door is provided with a handle or eyelet portion 3 for manual operation. 45

An upper and a lower contact indicated generally by the reference characters 4 and 5 are provided and may consist of approximately U-shaped metal members formed of strap material and indicated at 6 and 7 respectively. These members, as may be seen from Figure 5, 50 55

have a relatively flat transverse portion 8 to which the upper and lower contact fingers are secured. For example, the upper contact may comprise a pair of laminated spring contact fingers 9 joined by a transverse portion 10 secured to the flat portion 8 of the member 6 by means of screws 11.

The lower contact is provided with U-shaped contact spring arms 12 which are backed by an outer spring member 13, as may be seen most clearly from Figure 4. Each of the upper and lower contacts is provided with a clamping plate 14 which is adapted to clamp an incoming conductor or lead-in wire when such plate is drawn forwardly by means of screws or bolts 15 which are threaded into the plates.

These screws or bolts are preferably provided with polygonal heads and may have slots for the reception of a screw driver so that the lineman can use either a socket wrench or a screw driver to draw the plates 14 forwardly to clamp the incoming leads. Preferably the members 6 and 7 are notched out as indicated at 16 and 17 to facilitate the insertion of the leads between the plates 14 and the portions 8.

The members 6 and 7 have rearwardly extending legs which are cemented, leaded or otherwise secured to the housing 1. Preferably the housing is provided with the usual intermediate barrier 18.

A pair of supporting hook like members 19 are provided for the reception of the trunnions hereinafter described and are provided with side walls 20 and a transverse wall or member 21. The members 20 and 21, as shown in Figure 1, are cemented, leaded or otherwise secured to the housing 1.

The housing 1 is adapted to be carried by any suitable support and may be mounted vertically as shown in Figures 1 and 2 or may be mounted in a slanting position as shown in Figure 3.

The door carries a guide or sleeve 22 which is permanently secured thereto and which slidably receives the fuse tube 23. The sleeve 22 is provided with shouldered portions or projections 24 which have abrupt front faces 25 and slanting rear cam like faces 26.

The door and fuse tube assembly is normally held closed as the projections 24 are received behind the inwardly curved or bent portions 27 of the contact fingers 12, see Figure 4, and thus the door and fuse tube assembly is yieldingly held closed. Further, when the fuse tube is in its operative position as shown in Figure 1, the upper contact fingers 9 also assist in holding the fuse tube and door assembly in closed position as such fingers are upwardly arched and fit over the projections 28 formed on the upper contact 29 of the fuse tube, though these fingers are not relied upon to hold the door closed when the fuse tube drops downwardly as shown in Figure 2, as the engagement of the inward projections 27 of the contact fingers 12 with the portions 24 of the sleeve holds the door closed.

The door is provided with a rearwardly projecting upper portion 30 which receives a pin 31 integral with the screw cap 32 of the fuse tube. The door may also be provided with a bracing web 33 which joins the projecting portion or 70 apertured tongue 30 and also forms a stop against which the cap 32 of the fuse tube bears.

A fuse link is positioned within the fuse tube and is provided with a fusible portion 34 and a flexible leader 35 which latter projects out of the 75 open bottom end of the fuse tube and is prefer-

ably guided through a notch 36 formed in the bottom edge of the fuse tube, as shown in Figure 1. The fuse link has an upper button-head which is clamped in place by the screw cap 32.

The sleeve 22 is provided with a rearwardly projecting arm 37 which is equipped with a transversely extending cylindrical portion 38 terminating in trunnions 39. The trunnions 39 are adapted to be removably received within the hook supports 19, as shown in Figures 1 and 2. It is to be noted particularly from Figure 6, that the arm 37 is offset and that the cylindrical portion 38 projects laterally from the arm. This cylindrical portion is cut away to provide a flat face 40, as shown in Figures 1, 2 and 6.

The arm 37 is provided with a rounded portion 41 which normally is positioned below the overhanging transverse portion 21 of the hook supports 19. The purpose of this construction is to guard against inadvertent detachment of the fuse tube and door assembly from the hook supports 19 as it is apparent that the assembly cannot be detached from the hook supports 19 until the assembly is rocked downwardly to position the flat portion 40 so as to allow it to clear the overhanging portion 21, as will be apparent from an examination of Figures 1 and 2. Under these conditions the assembly may be unhooked from the hook portions 19 and may be readily removed from the housing for refusing.

The lower portion of the fuse tube is provided with a collar 42 rigidly secured thereto and provided with a pair of rearwardly projecting ears 43 which carry the pintle pin 44, see Figure 2.

A link member 45 formed of two spaced plates and joined by a transverse portion 46 is pivotally carried by the pintle pin. A spring 47 is loosely coiled about the pin and urges the link 45 in a counterclockwise direction from the position shown in Figure 1 towards the position shown in Figure 2.

A lever 48 is pivoted between the arms of the link 45 by means of the pintle pin 49, see Figures 1 and 2, and is provided with a free forward end 50 which is slightly cut out to conform approximately to the contour of the fuse tube, as shown in Figures 4 and 6. The lever 48 extends rearwardly and is provided with a fuse link clamping tongue 51.

The link 45 and the lever 48 normally occupy the position shown in Figure 1 and the leader 35 of the fuse link is positioned beneath the lever 48 and is clamped between the clamping tongue or portion 51 of the lever and the cylindrical member 38 of the arm 37, and thus the use of a thumb nut is avoided.

It is preferable to form the portion 51 of the lever 48 with a projecting tongue 52 to facilitate refusing, as will hereinafter appear. The assembly of the link 45 and the lever 48 constitutes restraining means for restraining the fuse tube and also constitutes fuse link extracting means and thus forms a combined fuse link extracting means and restraining means.

The operation of the apparatus is as follows: Assuming the parts are in the position shown in Figure 1 and an overload occurs. The fuse link is ruptured and the lever 48 is released. The spring 47 rocks the link 45 in a counterclockwise direction carrying the pintle pin 49 of the lever 48 downwardly. In view of the fact that the portion 51 of the lever 48 bears against the fuse link, which link in turn bears against the cylindrical portion 38, it is apparent that the free end 50 of the lever 48 will move downwardly in 75

5 a very rapid manner, multiplying the rocking motion of the link 45 and quickly withdrawing any remaining portion of the fuse link. Finally the portion 51 of the lever 48 will clear the cylindrical portion 38 and will thus release any remaining portion of the fuse link, which latter will fall or be thrown from the device.

10 It is to be noted that due to the rocking motion of the link 45, that the pintle pin 49 will rock downwardly towards the open end of the 15 fuse tube and that the free end of the lever 48 will tend to rock downwardly and to the left of the pintle pin 49. The result of these two motions is that the free end 50 of the lever 48 will move approximately directly downwardly and will thus withdraw any remaining portion of the 20 fuse link by a pull exerted substantially directly downwardly, thus minimizing friction and permitting the use of a relatively stiffer leader.

25 In view of the fact that due to the action of the spring 47 the portion 50 of the lever 48 presses downwardly against any remaining portion of the fuse link and thereby accelerates such portion of the fuse link, it is apparent that there is a reactive upward thrust exerted on the fuse tube which holds the fuse tube with its upper contact in engagement with the stationary upper contact of the housing until after the fuse link extracting action has taken place, and consequently until after the circuit has been interrupted within the fuse tube, thus avoiding pitting of the upper contacts. Additionally, the reactive forces of the gases being discharged from the lower end of the fuse tube tend to hold the 35 fuse tube in its uppermost position until this blast of gases has ceased. The upward reaction is resisted by engagement of the collar 42 with the lower portion of the sleeve 22.

40 The fuse tube thereafter drops downwardly to the position shown in Figure 2 and it is to be particularly noted that the fuse link extracting means moves away from the live portion of the apparatus and consequently is electrically dead.

45 If desired, the arm 31, see Figures 1 and 2, may have a flat portion positioned below the lower contact 5 to thus prevent the upper edge of the door upon recoil from striking the adjacent portion of the housing.

50 In refusing the device, the lineman rocks the fuse link extracting means into the position shown in Figure 6 clear of the cylindrical portion 38 and moves the fuse link extracting means back into its initial position, at the same time pulling the leader of the fuse link into the position shown in Figure 6. Thereafter he rocks the fuse tube assembly so as to position the fuse link extracting lever above the cylindrical portion 38, the lug 52 of the portion 51 of such lever assisting in holding the fuse link against lateral shifting. Thereafter the portion 51 clamps the leader 35 of the fuse link against the cylindrical portion 38. The lineman then hooks the trunnions 39 into the hook supports 19 and rocks the door to closed position.

55 It will be seen that a drop-out fuse device has been provided in which the fuse tube slides downwardly after the fuse link has been ruptured and that the fuse link is discharged from the device.

60 It will be also seen that the lower end of the fuse tube assembly is dead when it projects downwardly from the housing as the fuse link extracting means has detached itself from engagement with any live portion of the apparatus.

65 Also it is apparent that the fuse link will be readily and quickly withdrawn from the fuse tube

70 with a minimum of friction due to the fact that the free end of the fuse link extracting lever exerts a pull substantially directly downwardly upon the fuse link.

75 The device may be easily refused when the door and fuse tube assembly are detached from the casing and this assembly may be readily repositioned after refusing by merely hooking the trunnions back into the hook supports and rocking the door to closed position.

80 Although this invention has been described in considerable detail, it is to be understood that such description is intended as illustrative rather than limiting, as the invention may be variously embodied and is to be interpreted as claimed.

85 I claim:

1. A housed type of drop-out fuse comprising a housing, a fuse tube and door assembly, supporting means including pivot means for supporting said fuse tube and door assembly from said housing, said fuse tube being mounted to drop outwardly from operative to inoperative position, restraining means carried by said fuse tube and movable therewith for normally restraining said fuse tube from motion from operative to inoperative 25 position, said restraining means cooperating with said supporting means adjacent said pivot means and moving away from said supporting means when said fuse tube moves to inoperative position, and a fuse link within said fuse tube 30 controlling said restraining means.

2. A housed type of drop-out fuse comprising a housing, a fuse tube and door assembly, supporting means including pivot means for supporting said fuse tube and door assembly from said housing, said fuse tube being mounted to drop outwardly from operative to inoperative position, restraining means carried by said fuse tube and movable therewith for normally restraining said fuse tube from motion from operative to inoperative 40 position, said restraining means cooperating with said supporting means adjacent said pivot means and moving away from said supporting means when said fuse tube moves to inoperative position, and a fuse link within said fuse tube 45 controlling said restraining means, said restraining means being electrically dead when said fuse tube has moved to inoperative position.

3. A housed type of drop-out fuse comprising a housing, a fuse tube and door assembly, supporting means including pivot means for supporting said fuse tube and door assembly from said housing, said fuse tube being mounted to drop outwardly from operative to inoperative position, restraining means carried by said fuse tube and movable therewith for normally restraining said fuse tube from motion from operative to inoperative 55 position, said restraining means cooperating with said supporting means adjacent said pivot means and moving away from said supporting means when said fuse tube moves to inoperative 60 position, and a fuse link within said fuse tube controlling said restraining means, said restraining means withdrawing any remaining portion of said fuse link upon rupture of said fuse link.

4. A housed type of drop-out fuse comprising a housing, a fuse tube and door assembly, supporting means including pivot means for supporting said fuse tube and door assembly from said housing, said fuse tube being mounted to drop outwardly from operative to inoperative position, restraining means carried by said fuse tube and movable therewith for normally restraining said fuse tube from motion from operative to inoperative 70 position, said restraining means cooperating 75

with said supporting means adjacent said pivot means and moving away from said supporting means when said fuse tube moves to inoperative position, and a fuse link within said fuse tube controlling said restraining means, said restraining means withdrawing and discharging any remaining portion of said fuse link upon rupture of said fuse link.

5. A drop-out type of fuse assembly comprising
10 a stationary portion, a drop-out fuse tube having
an open lower end, supporting means for supporting
said fuse tube from said stationary portion,
said fuse tube having movement with reference to
said supporting means and movable from opera-
15 tive to inoperative position, a fuse link within said
fuse tube, and combined fuse link extracting and
fuse tube restraining means carried by said fuse
tube and having a portion movable downwardly
20 from the open lower end of said fuse tube to ex-
tract any remaining portion of the fuse link by a
pull substantially in line with said fuse tube and
to release the fuse tube upon rupture of said fuse
link.

6. A drop-out type of fuse assembly comprising
25 a stationary portion, a drop-out fuse tube having
an open lower end, supporting means for sup-
porting said fuse tube from said stationary por-
tion, said fuse tube having movement with refer-
ence to said supporting means and movable from
30 operative to inoperative position, a fuse link with-
in said fuse tube, and combined fuse link extract-
ing and fuse tube restraining means carried by
said fuse tube and having a portion movable
downwardly from the open lower end of said fuse
35 tube to extract any remaining portion of the fuse
link by a pull substantially in line with said fuse
tube and to release the fuse tube upon rupture of
said fuse link, said portion being located to the
side of said fuse tube and adjacent the open lower
40 end thereof, whereby said portion is protected
from the blast of gases from said fuse tube and
leaves the bore of said fuse tube unobstructed.

7. A drop-out type of fuse assembly comprising a stationary portion, a drop-out fuse tube having an open lower end, supporting means for supporting said fuse tube from said stationary portion, said fuse tube having movement with reference to said supporting means and movable from operative to inoperative position, a fuse link within 45 said fuse tube, a link pivoted to said fuse tube adjacent the open lower end and having an outer end movable downwardly, a lever pivoted to the outer end of said link and having a free end located adjacent the open lower end of said fuse 50 tube and movable downwardly with reference to said fuse tube, said fuse link normally restraining said lever, and means supported by said stationary portion and cooperating with said lever to hold said fuse tube in operative position.

55

60 8. A drop-out type of fuse assembly comprising a stationary portion, a fuse tube having an open lower end, means supported from said stationary portion for slidably guiding said fuse tube, a link pivoted to said fuse tube adjacent the open lower end and having a free end projecting from said fuse tube, a lever pivoted to the free end of said link and having a first end adjacent the open lower end of said fuse tube and having a second end projecting laterally therefrom, a fuse link located within said fuse tube and passing beneath said first end of said lever, and a relatively stationary member cooperating with said second end of said lever, whereby said fuse tube is normally restrained

against sliding, said fuse link upon rupture releasing said first end of said lever.

9. A drop-out type of fuse assembly comprising a stationary portion, a fuse tube having an open lower end, means supported from said stationary portion for slidably guiding said fuse tube, a link pivoted to said fuse tube adjacent the open lower end and having a free end projecting from said fuse tube, spring means urging the free end of said link downwardly, a lever pivoted to the free end of said link and having a first end adjacent the open lower end of said fuse tube and having a second end projecting laterally therefrom, a fuse link located within said fuse tube and passing beneath said first end of said lever, and a relatively stationary member cooperating with said second end of said lever, whereby said fuse tube is normally restrained against sliding, said link upon rupture releasing said first end of said lever. 5 10 15 20 25

10. A housed type of drop-out fuse comprising a casing, a door, a fuse tube slidably carried by said door, supporting means pivotally supporting said door from said housing, a link pivotally mounted on said fuse tube adjacent one end of said fuse tube and having a free end, a lever pivoted intermediate its ends to the free end of said link and having a first end located adjacent said fuse tube and having a second end cooperating with said supporting means to restrain said fuse tube against motion, and a fuse link within said fuse tube releasably holding said lever against motion.

11. A housed type of drop-out fuse comprising a housing, a fuse tube and door assembly, supporting means including pivot means for pivotally supporting said assembly from said housing, said fuse tube being slidably carried by said door, restraining means carried by said fuse tube and cooperating with said supporting means adjacent said pivot means to restrain said fuse tube against sliding, and a fuse link within said fuse tube controlling said restraining means. 35 40

12. A housed type of drop-out fuse comprising a housing, a fuse tube and door assembly, supporting means including pivot means for pivotally supporting said assembly from said housing, said fuse tube being slidably carried by said door, restraining means carried by said fuse tube and cooperating with said supporting means adjacent said pivot means to restrain said fuse tube against sliding, and a fuse link within said fuse tube controlling said restraining means, said restraining means moving completely away from said pivot means upon rupture of said fuse link. 50 55

14. A drop-out type of fuse assembly comprising a stationary portion, a drop-out fuse tube having an open lower end, supporting means for supporting said fuse tube from said stationary portion, said fuse tube having movement with 70 75

reference to said supporting means and movable from operative to inoperative position, a fuse link within said fuse tube, and a double jointed mechanism constituting combined fuse link extracting and fuse tube restraining means including a lever having a movable pivot point intermediate the ends of said lever and said lever having a forward end adjacent the lower open end of said fuse tube and having a rear end cooperating with said supporting means to restrain said fuse tube, said fuse link passing out of the lower open end of said fuse tube and over the forward end of said lever.

15. A drop-out type of fuse assembly comprising a stationary portion, a drop-out fuse tube having an open lower end, supporting means for supporting said fuse tube from said stationary portion, said fuse tube having movement with reference to said supporting means and movable from operative to inoperative position, a fuse link within said fuse tube, and a double jointed mechanism constituting combined fuse link extracting and fuse tube restraining means including a lever having a movable pivot point intermediate the ends of said lever and said lever having a forward end adjacent the lower open end of said fuse tube and having a rear end cooperating with said supporting means to restrain said fuse tube, said fuse link passing out of the lower open end of said fuse tube and over the forward end of said lever, said combined fuse link extracting and fuse tube restraining means being carried by said fuse tube and movable therewith and being electrically dead after said fuse tube has moved to inoperative position.

16. A drop-out type of fuse assembly comprising a stationary portion, a slidably mounted drop-out fuse tube having an open lower end, supporting means supported from said stationary portion and slidably holding said fuse tube, a double jointed mechanism constituting a combined fuse link extracting and fuse tube restraining means including a lever carried by the fuse tube and releasably restraining said fuse tube from motion and having a free end movable in a direction substantially downwardly from the lower end of the fuse tube, and a fuse link within said fuse tube normally restraining said lever from motion.

17. A drop-out fuse assembly comprising a stationary portion, a fuse tube having an open lower end, supporting means supported from said stationary portion for slidably guiding said fuse tube, a link pivoted on said fuse tube adjacent the lower end and having a free end projecting from said fuse tube, a spring urging the free end of said link downwardly, a lever pivoted intermediate its ends to the end of said link and having a forward end adjacent the open lower end of said fuse tube and having a rear end adjacent said supporting means, and a fuse link located within said fuse tube and extending outwardly through the open lower end thereof and passing beneath said forward end of said

lever and clamped between the rear end of said lever and said supporting means, whereby said fuse tube is normally restrained against sliding and whereby upon rupture of said fuse link the forward end of said lever will extract any remaining portion of said fuse link, said fuse link being subsequently discharged from said assembly.

18. A housed type of drop-out fuse comprising a casing, a door, support means pivotally supporting said door from said casing and having a transversely extending portion adjacent the pivot point, a fuse tube slidably carried by said door and having an open lower end, a fuse link within said fuse tube projecting outwardly of said open lower end, a combined fuse link clamping and fuse tube restraining means carried by said fuse tube and movable bodily with said fuse tube when said fuse tube slides with reference to said door, said lever having a forward end over which said fuse link is looped and having a rear end releasably clamping said fuse link between itself and the transversely extending portion of said support means.

19. A stationary contact construction for an electrical device comprising a U-shaped supporting member having the legs thereof adapted for attachment to a suitable support and having a relatively flat transverse portion, yielding contact means secured to said relatively flat transverse portion, a conductor clamping plate positioned adjacent said relatively flat transverse portion, and attaching means accessible from the front for drawing said plate towards said relatively flat portion to clamp a conductor.

20. A stationary contact construction for an electrical device comprising a U-shaped supporting member having the legs thereof adapted for attachment to a suitable support and having a relatively flat transverse portion, yielding contact means secured to said relatively flat transverse portion, a conductor clamping plate positioned rearwardly of said relatively flat transverse portion, and attaching means accessible from the front extending through said relatively flat transverse portion and threaded into said clamping plate, whereby a conductor may be clamped between said plate and the rear face of said relatively flat transverse portion.

21. In a housed drop-out fuse construction, a housing, a door for said housing, supporting means supported from said housing and carrying said door and including a sleeve, said housing having stationary contacts, a fuse tube slidably carried by said sleeve, a fuse link within said fuse tube normally electrically connecting said stationary contacts, an abutment carried by said supporting means and spaced from said sleeve, and a fuse link extracting member carried by said fuse tube and detachably interlocking with said abutment and controlled by said fuse link.

WILLIAM O. SCHULTZ.
